E. SNYDER

SASH HOLDER

Filed July 12, 1927

FIG. 1.

FIG. 2.

FIG. 3.

FIG. 4.

FIG. 5.

EDWARD SNYDER

Inventor

By Henry P. Korman
his Attorney

UNITED STATES PATENT OFFICE.

EDWARD SNYDER, OF FINLEY PARK, ILLINOIS.

SASH HOLDER.

Application filed July 12, 1927. Serial No. 205,179.

This invention relates in general to window controls and more particularly to an economically constructed and efficient device for retaining a window sash in an adjusted set 5 position.

One object of this invention is the production of a window control which eliminates the use of window weights and ropes or chains and yet will hold the window sash in an adjusted set position.

Another object of this invention is the production of a window control which not only will hold the sash in an adjusted set position, but will at all times take up unnecessary play between the window sash and the casing, thereby preventing rattling of the sash.

A still further object of this window control is the production of a simple article of manufacture for the purposes set forth, which may be readily applied to a window sash without the aid of screws or bolts or any other auxiliary securing means, thus permitting an inexperienced person to mount the control in an operative position upon the sash.

With the foregoing and similar objects in view, reference is directed to the accompanying drawing, in which like reference numerals indicate like parts in the several views, 30 wherein,

Fig. 1 is a fragmentary elevation of a window casing and a pair of sashes partly broken away and showing a pair of my window controls in operation.

Fig. 2 is a fragmentary perspective view of a window sash, showing the usual rope knot receiving socket;

Fig. 3 is a front elevation of the window control;

Fig. 4 is a side elevation of the device; and

Fig. 5 is an elevation of a portion of the device, partly broken away and showing the manner in which the lug is attached to the body portion of the control.

With further reference to the drawing, 1 denotes a usual form of window casing having the sashes 2 movable therein in the usual manner. It will be noted, however, that the usual balance weights and ropes or chains 50 have been eliminated and in lieu thereof the window control is illustrated in use.

This invention is an article of manufacture and comprises a bowed spring body portion 5 having a straight supporting end portion 6 and a straight bearing end portion 6'. The body portion 5 having the end portions

6 and 6' is formed from a single piece of resilient sheet metal, which is elongated although being comparatively wide, thereby presenting a strong resilient action.

The retaining lug 7 is somewhat elongated although in cross section it is round. This lug 7 has a small neck 8, which neck 8 extends through the supporting end portion 6 and is flattened, as illustrated in detail in Fig. 5, thereby fixedly securing the lug 7 to the spring body portion 5. The outer end of the lug 7 is preferably beveled as indicated at 9 for the purpose of facilitating the mounting of the window control upon the window sash 2, as hereinafter more fully set forth.

The sash 2 disclosed in Fig. 2 has the usual rope knot receiving socket 3 and if it happens that a sash does not have such a socket, it is obvious that one may be easily formed therein. When the sashes 2 are mounted within the window casing 1, as illustrated in Fig. 1, the side edges of the sashes are spaced slightly from the inner face of the casing 1 to provide a space 4 in which the window controls may move as the sashes 2 are moved vertically within the casing 1.

As is shown in Fig. 1, all that is necessary to place the window control upon the sash 2 is to insert the lug 7 in the socket 3. It is apparent that the manner in which the lug 7 is fixed mounted upon the supporting end portion 6 makes a very strong and substantial construction. Therefore, when the lug 7 is fitted within the socket 3 the spring body portion 5 will be firmly supported in an operative position upon the sash 2. The bearing end portion 6' bears upon the edge of the sash and is free to move longitudinally of the window sash when the spring body portion 5 flexes. The spring body portion 5 bears firmly upon the inner face of the casing 1, as illustrated in Fig. 1, and as the lug 7 is fitting within the socket 3, the sash will be held in an adjusted position. The sashes may be moved up or down at will and at such times the window controls will slide upon the casing in unison with the movement of the sashes. As soon as the manual movement of the sashes is discontinued the engagement of the spring body portions 5 with the casing 1 will hold the sashes 2 in adjusted positions.

It is apparent that as the spring body portions 5 engage the casing 1 so firmly as to hold the sashes in set positions the sashes will at all times be prevented from shaking or rattling within the casing.

The window control herein described may be manufactured at a minimum cost, since it comprises only two original parts which are fixedly connected together to present a substantial unit construction. No additional parts are necessary to the proper operation of this invention and no screws or similar securing means are necessary to hold this device in an operative position upon the sash 2.

From the illustration of the drawing and the foregoing description of the construction and operation of this window control it is clear that counter balance weights, chains or ropes and similar means for holding the sashes in adjusted positions are unnecessary. It is easy to mount this window control in an operative position, for it is only necessary to insert the lug 7 within the socket 3 and then replace the sash 2 within the casing 1 to allow the spring body portion to bear upon the casing. This bearing action holds the lug 7 within the socket 3, while the lug 7 retains the spring body portion 5 in an operative position upon the sash 2.

There has thus been produced a window control which may be readily mounted upon

a window sash for the purposes set forth and be properly held in an operative position without auxiliary securing means, this invention, because of its simplified construction being economically produced and having no intricate parts liable to result in trouble during severe usage.

Having described this invention, what I claim as new and desire to cover by Letters Patent is:

An article of manufacture of the character described, comprising a bowed spring body portion having a straight supporting end portion and a straight bearing end portion, the end portions being in alignment with each other, whereby as the body portion bears upon a casing the end portions will be firmly pressed against a sash, and a cylindrical socket engaging lug fixedly mounted upon said supporting end portion, the outer end of said lug being beveled, thereby permitting easy inserting into a socket, as and for the purposes set forth.

In testimony whereof I hereunto affix my signature.

EDWARD SNYDER.
